(57) **CLAIM**

The ornamental design for a coin purse, as shown and described.

DESCRIPTION

FIG. 1 is a front top perspective view according to the present invention.

FIG. 2 is a top view of the coin purse.

FIG. 3 is a bottom view of the coin purse.

FIG. 4 is a left side elevational view of the embodiment.

FIG. 5 is a right side elevational view of the embodiment.

FIG. 6 is a front side elevational view of the embodiment; and, FIG. 7 is a rear side elevational view of the embodiment.

The broken line showing the coin slit and guide member is for illustrative purposes only and forms no part of the claimed design.
